Patented Nov. 1, 1921.

UNITED STATES PATENT OFFICE.

JAMES W. RILEY, OF LOS ANGELES, CALIFORNIA.

SANITARY VENDING-TRAY FOR EATABLES.

1,395,975.

Specification of Letters Patent.

Patented Nov. 1, 1921.

Application filed March 16, 1920. Serial No. 386,335.

To all whom it may concern:

Be it known that I, JAMES WELK RILEY, a citizen of the United States, residing at Los Angeles, in the county of Los Angeles and State of California, have invented new and useful Improvements in Sanitary Vend- 5 ing-Trays for Eatables, of which the following is a specification.

This invention relates to vending para- 10 phernalia and has for its object to provide a sanitary vending tray for edibles and particularly to provide a device of this kind that provides ample capacity for carrying the goods to be vended and at the same time 15 to leave the same fully exposed to view but protected from contamination by street dust when the tray is carried about by the vender. The invention consists of the construction, the combination, and in details and arrange- 20 ments of the parts, an embodiment of which invention is illustrated in the accompanying drawings and described and claimed herein- after.

Figure 1 is a perspective view showing the 25 device applied to the body of the vender.

Fig. 2 is a perspective of the detached device with parts in section.

Fig. 3 is a vertical transverse section indicating a means for securing complementary 30 parts of the cover in folded relation.

Fig. 4 is a plan view of the blank of the cover.

Street venders of confections commonly carry the same in exposed position in a tray 35 a form of which is shown as comprising a receptacle having a bottom 2 with a marginal flange 3 of suitable height surrounding the bottom 2. This receptacle or tray is designed to be suspended from the shoulders 40 of the vender by means of shoulder straps or other suitable harness indicated at 4 having front members attached as at 5 to the side flanges, thus enabling the tray to be disposed across the front of the waist of the 45 wearer in a convenient position to be reached and exposing the goods to be sold.

The present invention consists of a cover forming a window and shield which while exposing the goods to view protects the same 50 from dust. The cover may be made of a single piece of bendable transparent material such as celluloid. The blank may be shaped as desired to conform to a given type of receptacle a form of which blank is shown 55 in Fig. 4 as comprising a substantially ob-

long body portion 6 the outer edge of which is inwardly slotted at 7 and along the outer edge are provided perforations 8. Extending from the intermediate portion of the opposite longitudinal edge is a leaf part 9 60 somewhat shorter than the main body part 6 and the inner portions of the end edges 10 of the leaf 9 are cut on an inwardly extending curve as at 11 merging into the longitudinal line 12. The outer corner of the leaf 65 9 may be perforated as at 13.

The blank of this kind is adapted to have the intermediate longitudinal edge between the slits 7 laid around on the inside surface of the flange 3 of the tray while the corner 70 portions 14 are sprung out over the outer surface of the flange; the latter extending upwardly into the slits 7-7. Thus the body portion 6 extends across the front of the tray and around the corners and sides as 75 shown in Fig. 2 and suitable fastening means are passed through the apertures 8 to secure body portions 6 in an upright wall-forming position.

When thus arranged the leaf 9 may be 80 folded to form an upper front corner 9' and the end edge portions 10 of the leaf can be folded down over the upper edges 12 of the wall and secured to the wall by suitable means comprising a bolt 15 passed through 85 washers 16 between which the overlapped portions of the leaf 9 and the side walls are clamped. The ends of the leaf 9 thus make a substantially tight joint over the upper edges 12 and an effective cover is provided 90 yet permitting a clear view of the interior. Access may be had to the goods through the opening formed at the rear of the cover forming members when they are assembled.

Various changes may be made without departing from the spirit of my invention as 95 claimed.

What is claimed is:

A sanitary cover for street venders' trays, 100 comprising a single sheet of pliant transparent material, cut to form a substantially oblong body portion, a leaf portion extending from the intermediate portion of the upper longitudinal edge of said body portion and being substantially shorter than the body 105 portion, the ends of said leaf portion being cut inwardly from the juncture of the upper longitudinal edge of the body portion therewith, said cuts being an extension of the said edge, said body portion being bent to form 110

a front and ends, and the leaf portion being bent downwardly to form the top, the end portions thereof being bent downwardly along lines extending at substantially right angles from the upper longitudinal edge of the body portion and from the ends of the inwardly extending cuts, said downwardly bent end portions extending over the ends of the body portion and secured thereto, the whole being secured to the tray. In testimony whereof I have signed my name to this specification.

10

JAMES W. RILEY.
